UNITED STATES PATENT OFFICE.

HUGO WIEGAND, OF THURINGIA, GERMANY.

EYE CARRIER AND EYELID FOR DOLLS' EYES.

Application filed March 12, 1927, Serial No. 174,911, and in Germany November 27, 1926.

This invention relates to an eye carrier and eye lids for dolls' eyes, and it is characterized in that, in a supporting frame fixed in a doll's head in a well known manner, the doll's eyes are mounted in corresponding apertures to open in an upward direction so that they can be turned to all sides and are rigidly supported to render it difficult for the eyes to be pressed out of the eye holes towards the inner side of the head, so that the axle which connects the eye lids traverses the eye carrier at the center like a scale beam and is rotatably journalled in this carrier. Owing to this arrangement no perceptible movement of the eye lids occurs at first when the doll's head is bent at a slight angle rearwardly whilst the lid is closed only when approximately at a 90° angle or incline of the head or in a reclining position. The eye carrier consists of a plate of sheet iron, celluloid, ceramic material, or the like, supported fixedly at its opposite ends to the head and in which two circular apertures, of less diameter than that of the eyes, are formed. These apertures are spaced at a distance which corresponds to the distance between the eyes. The edges of these apertures are bent rearward and slightly inwardly inclined or cupped. The eyes, which are connected at their rear sides by articulated wires, are inserted from the front of the plate through the circular apertures of the plate and by reason of their peculiar mounting are capable of turning in the eye carrier towards all sides under the action of a weight flexibly supported from the upper portion of the head and connected to said articulated wires. The apertures in the plate might, however, be made without sunk or pressed in edges, so that the plate is perfectly plain. At the center of the carrier plate, between the two apertures for the eyes, a vertical slot is formed through which passes the lever for the eye lids, said lever being pivotally fixed in the carrier slot. The distance of the axle which connects the two eye lids from the pivot point of the eye lid lever is preferably made as short as possible. As the eyes are mounted to turn in the carrier in all directions they simulate, in combination with the movable eye lids, a true imitation of the natural movements of the human eyes. That is, when the doll's head is being moved in a suitable manner the eyes can turn from one side to the other or when moved in a rearwardly inclined direction they will move toward closing, and if a slight angular tilt be given the head during such movement, the eyes will have imparted thereto a roll. The eyes are consequently adapted to turn in any direction and they form a practical substitute for the so-called sleeping eyes, or for the funny eyes as well as for the expensive so-called hole-eyes which are used in connection with the funny eyes. The improved carrier securely holds the eyes so that they cannot drop during transport, nor can they be pressed in by a pressure with the fingers. The improved carrier is cheap to manufacture and of very simple construction so that the eyes can be inserted by unskilled persons, the cost of manufacture of the dolls being thus further reduced.

An embodiment of the invention is illustrated, by way of example, in the accompanying drawing, in which:

Fig. 1 shows a horizontal section through a doll's head at the height of the eyes.

Fig. 2 is a vertical section taken intermediate of the eyes.

The eye carrier 1 consists of a rectangular plate the ends 2 of which are bent to serve as supporting elements to be cemented on the inner surface of the head. The eye carrier 1 has two circular apertures 3, the edges 4 of which are bent inward to form sliding surfaces for the eyes 5. The plate for the eye carrier 1 might also be perfectly plain so that the apertures 3 have no inwardly bent edges 4. The eyes 5 are inserted from the front of the carrier through the circular apertures 3 and connected with one another behind the plate 1 by articulated wires 6. The weight 7 is suspended in known manner from the upper portion of the doll's head. The eye lids 8 are connected the one with the other by an axle 9 rigid with the lid lever 10. A vertical slot 11 is formed in the carrier plate 1 intermediate the apertures 3, and through which passes the lid lever 10 which is pivotally mounted on the carrier plate by means of a pin 12. The distance of the axle 9 from the pivot point 12 is as short as possible.

Claims:

1. Arrangement for the eyes and eye lids in dolls' heads comprising in combination, a rectangular plate having two circular apertures and a vertical slot between said apertures, two eye balls mounted for oscillation

in said apertures of said plate, articulated wires connecting said eyeballs behind said plate, a weight on said wires and suspended from the upper wall of the doll's head, two eye lids one for each hole of the doll's head, a horizontal axle connecting said eye lids, a lever fixed to said lid axle and passing through the vertical slot of said carrier plate, and fulcrumed on said plate, and a weight at the free end of said lid lever.

2. Arrangement for the eyes and eye lids in dolls' heads comprising in combination a rectangular plate of any suitable material having two circular and cupped apertures and also having a vertical slot between said apertures, a supporting element at each end of said plate and attached to the inner surface of the doll's head, two eye balls of greater diameter than and mounted, respectively, in said circular apertures of said plate for oscillatory movements, weight-actuated means connecting said eyes for movement in unison, two eye lids, one in each hole of the doll's head, a horizontal axle connecting said eye lids, a lever fixed to said lid axle and passing through said vertical slot of said carrier plate, a pivot pin pivotally securing said lid lever in said plate, and a

weight carried by the free end of said lid lever.

3. The combination with a doll's head provided with eye apertures, of a plate secured at its ends rigidly to the head and provided with two eye sockets, two oscillatory eyes mounted in said sockets and connected together for unitary movements, a weight for controlling the movements of said eyes, two connected lids journaled in the plate for vertical swinging movement between the eyes and the apertures of the head, and a weight connected to said lids.

4. The combination with a doll's head provided with eye apertures, of a plate secured at its ends rigidly to the head and provided with two eye sockets, two oscillatory eyes mounted in said sockets and connected together for unitary movements, a weight for controlling the movements of said eyes, two connected lids journaled in the plate for vertical swinging movement between the eyes and the apertures of the head, and a weight-actuated lever connected to the lids.

In testimony whereof I have hereunto set my hand.

HUGO WIEGAND.
